LEONARD ATWOOD, OF FARMINGTON, MAINE.

DRIVING MECHANISM FOR ELEVATORS AND THE LIKE.

1,110,248.

Specification of Letters Patent.

Patented Sept. 8, 1914.

Application filed April 3, 1913. Serial No. 753,578.

To all whom it may concern:

Be it known that I, LEONARD ATWOOD, a citizen of the United States of America, and a resident of Farmington, county of Franklin, and State of Maine, have invented certain new and useful Improvements in Driving Mechanism for Elevators and the like, of which the following is a specification.

This invention has reference to improvements in driving mechanism for elevators, lifts, hoisting apparatus and the like which are operated by means of ropes or cables that pass over a hoisting drum.

The present invention has for its special purpose to avoid that a heavy car and counterweight is required to produce the necessary friction for effecting the work. This in time consumes an unnecessary quantity of power to operate the elevator lift or hoisting apparatus. Certain machines require 600 pounds of dead load to produce sufficient friction to lift 100 pounds of live load which makes the car very heavy and the counterweight accordingly so.

By winding the cables over the hoisting drum one full turn and one half turn, in conjunction with the detailed construction hereinafter described, increased friction of the cables on the drum is produced which permits of using a relatively light car and counterweight. Idlers and secondary pulleys for the cables are avoided and the car stops automatically at the desired point, which is not the case when the cables are tending to slip on the drum. The invention further consists in the construction of the drum and its arrangement on the motor shaft which is splined to one hub while a stationary feed shaft with outer thread surrounds part of the motor shaft and engages the inner threaded portion of a second hub of the drum whereby the drum is adapted to move to and fro in a forward and backward direction, all as will be fully described hereinafter with reference to the accompanying drawing in which:

Figure 1 represents diagrammatically an elevator embodying the rope or cable arrangement for obtaining high friction. Fig. 2 illustrates the drive mechanism for an elevator in side elevation, and Fig. 3 is a longitudinal section on line 3-3 of Fig. 2.

Similar characters of reference denote like parts in all the figures.

In Fig. 1 of the drawing an elevator is diagrammatically shown in which *a* repre-

sents a hoisting drum and *b* the rope or cable passing once fully around the drum and over the top half portion of the same. Suspended from one end of the rope is the counterweight *c* while the car *d* is suspended from the other rope end. This diagrammatical figure is purposed to simply illustrate the arrangement of the ropes or cables on the hoisting drum. The rope or cable *b* thus produces more than three times the friction than is produced if the rope passes only over the top half portion of the drum. For rendering this rope arrangement possible the hoisting drum is provided with one continuous helical thread having a continuous groove *e* as shown in Fig. 2.

The driving mechanism illustrated in Fig. 2 comprises a substantial frame work *f*. Upon the part of the frame shown to the left there is mounted reducing mechanism inclosed in the reducing case *g*. In connection with the reducing mechanism is the motor shaft *h* for applying power. A bearing *i* is mounted on the frame part shown to the right in Fig. 2. The reducing mechanism is provided with the driving shaft *j* for the drum extending over to the bearing *i*. The shaft *j* has a longitudinal groove *j'* which serves for splining the shaft to the drum. A threaded feed shaft *k* surrounds the right portion of the shaft *j* and extends into the bearing *i* where it is permanently secured by means of a screw *l*. The drum *a* is provided with two hubs *m*, *n*. The hub *m* has a lateral slot *m'* through which passes a feather *o*. Thus the driving shaft *j* is splined to the hub *m* and the drum moves with it. The hub *n* at the other side of the drum is interiorly threaded and engages the thread of the feed shaft *k* whereby, during the rotation of the driving shaft *j* the drum travels along the feed shaft *k* in both a forward or backward direction in accordance with the direction of the rotation of the shaft *j*. In Fig. 2 of the drawing the drum *a* is shown to have traveled on the feed shaft *k* and the driving shaft *j* to near the end of the shaft slot *j'*. When the rotation of the shaft *j* is reversed the drum travels toward the right because the feed shaft *k* is permanently secured in the bearing *i*.

As previously mentioned the hoisting drum *a* has one continuous thread with one continuous helical groove *e*. The plurality of cables *p*, *p'*, etc., therefore always retain their initial position because the drum per-

forms a horizontal motion both in a forward and backward direction leaving the ropes always in the same position relative to the top center portion of the car. It is evident 5 that the threads of the hoisting drum and its feed shaft must correspond. Accordingly an idle wheel for guiding the ropes is not necessary and completely dispensed with by virtue of the increased friction produced 10 by the novel arrangement of the ropes or cables on the hoisting drum whereby a lighter car and counterweight may be used avoiding thus a large amount of dead weight and saving power.

15 I claim as my invention:

1. Driving mechanism for elevators, lifts and hoisting apparatus, comprising a hoisting drum with threaded hub and helical rope groove, ropes in said groove around 20 the drum, a driving shaft splined to the drum, and a permanently fixed, exteriorally threaded feed shaft, loosely on the driving shaft and engaging the threaded hub of the drum.

25 2. Driving mechanism for elevators, lifts, and hoisting apparatus, comprising a driving shaft with longitudinal spline groove in its inner portion, a permanently fixed, exteriorally threaded feed shaft loosely on the

driving shaft, a hoisting drum threaded on 30 the feed shaft and having a helical rope groove, ropes in said groove around the drum, a hub on the drum with slot and a feather therein traveling in the spline groove.

3. Driving mechanism for the hoisting drum of elevators and lifts, comprising a drum, a driving shaft splined to the drum, a hub on the drum with feather traveling in the spline groove, a second hub on the 40 drum with interior thread, and a permanently fixed feed shaft with an exterior thread in operative engagement with the inner thread of said second hub.

4. In driving mechanism for elevators and lifts, a hoisting drum with helical groove, ropes in the said groove wound around the drum for avoiding the raising of dead weight, a driving shaft splined to the drum, a stationary feed shaft loosely on the inner end portion of the driving shaft, and an interiorly threaded hub on the drum engaging the thread of the feed shaft.

Signed at Boston, Mass., March 26th 1913.
LEONARD ATWOOD.
